UNITED STATES PATENT OFFICE.

JOHN WILLIAM WALKER, OF BATLEY, ENGLAND, ASSIGNOR OF ONE-HALF TO PLATT BROTHERS AND COMPANY LIMITED, OF OLDHAM, LANCASTER, ENGLAND.

MOVABLE BACK FOR APRON FEEDERS.

Application filed June 6, 1922. Serial No. 566,356.

To all whom it may concern:

Be it known that I, JOHN WILLIAM WALKER, a subject of the King of Great Britain and Ireland, residing at 8 Russell Street, 5 Batley, in the county of York, England, have invented new and useful Improvements in Movable Backs for Apron Feeders, of which the following is a specification.

This invention relates to improvements in 10 or connected with automatic feeding machines for feeding fibrous or other material or substance to other machines as is well known in the textile trades, as for example for feeding cotton, wool, or waste to carding 15 engines, scribblers, drying machines, or other apparatus with which automatic feeding machines can be beneficially combined.

The novel features are hereafter described in detail and are illustrated by the attached 20 drawings, in which:

Fig. 1 is an end elevation of an automatic feeding machine, the figure illustrating certain of the improvements.

Fig. 2 is a side elevation of the machine.

Figs. 3, 4, 5 and 6 are separate detail views 25 and illustrate a modification in the means for holding the movable board back, or for permitting its advance, etc.

My improvements relate to that class of 30 automatic feeder which has a forward inclined spiked lattice forming the front of the hopper or receptacle, and a movable back or board forming one wall or the back of the hopper or receptacle.

Generally such spiked lattice is given considerable inclination and the fulcrum or pivotal point of the movable back or board has been in close proximity to the lower front extremity of the said inclined spiked 40 lattice. Thus, at the bottom of the hopper, and intermediate of the lattice and the movable back or board, a very restricted space has existed which is in section in the nature of an acute angle. This space may be fully 45 occupied following the initial filling, but once feeding has properly commenced the restricted space is quickly emptied and not again occupied and the distribution in the hopper is no longer even, the lattice lifting 50 the material from a higher level and a restricted area.

Under my invention I arrange the spiked lattice *a* (which lifts the material from the hopper A) in a position approximating to

the vertical, that is to say, the disposition of 55 the lattice is only a few degrees from the vertical. The bottom of the hopper consists of a grid *a'*, pivoted at *a²*, and adapted to swing upwardly, a fastening member *a³* being provided for retaining the grid in its 60 horizontal position. In addition, I pivot or hinge the movable back or board *b* as at the points *b', b'* some distance back from the bottom end of the lattice leaving an intervening 65 space between the two whereby the material no longer falls into or occupies at any time a narrow space in section like an acute angle.

The fulcrumed or pivoted movable back or board *b* forming the rear wall or back of the hopper is arranged to be automatically 70 turned on a fulcrum or moved in, as the hopper empties, by the action of weights which are mounted on the machine and connected thereto to this end.

In addition, means are provided for holding 75 said movable board *b* back and putting the weights out of action whilst the attendant fills the hopper and for automatically re-instating the weights when the attendant re-sets the movable back or board by a further 80 backward movement on completion of the filling.

Said movable back or board *b* is suitably 85 constructed and is fulcrumed as before stated, as for example at the points *b', b'*, 90 and has at its upper edge a projecting bar *b²* or bars which work over the curved tops *c'* of the hopper sides *c*, or in other suitable 95 fashion. From such projecting bar *b²* flexible ties *b³, b⁴*, extend, the same passing over 100 guide pulleys *b⁴, b⁵*, and being connected to a lower sliding box weight *d* over which can be superposed other box weights to the required amount. All the weights are suitably guided, as for example by two or more 105 upright bars *d', d'*, or in any other fashion which will permit the weights to rise and fall as required, the gradual descent of the weights pulling in the movable or pivoted back or board *b* as the material is lifted out 110 of the hopper by the spiked lattice *a*, as will be understood. Fulcrumed to the front corners of the hopper sides *c* are catch levers *e* each movable upon a pivotal stud *e'*, there 115 being a catch lever *e* at each side, the same having a spring *e²* and a projecting peg *e³*. The spring *e²* bears and acts on the peg *e³* and so protrudes a locking tooth or projec-

tion e^4 (forming part of the catch lever e) just above the curved tops e' of the hopper sides c whilst the peg e^5 limits the upward movement of the catch lever e . From each 5 catch lever e , a cranked projecting arm e^5 extends, the same projecting in the direction of the sets of movable weights. Supported on the lowest box weight d is a loaded upright lever f with stop pin f^2 , the lever f 10 being suitably fulcrumed as at f' and having a tooth f^3 with inclined edge. This tooth f^3 is intended to co-operate with the projecting arm e^5 from the catch lever e , in the sense, that when the weights (including 15 any superposed weights carried on the box weight d) move down (say an inch or more from their highest position) the tooth f^3 acts on the projecting arm e^5 and lowers or moves the catch lever e out of the path of the extremities of the projecting bar b^2 20 which extremities travel through an arc as the back or board b moves in, as will be understood.

The reason for this mechanism is, to enable the attendant to lock the movable back or board b in almost a fully pulled out position, and against the action of the weights d , whilst filling takes place.

Presuming filling is to take place, the attendant pulls back the movable board b until the extremities of bar b^2 latch behind the tooth element e^4 on the catch levers e, e , which thus hold said movable board b sufficiently fully open to permit filling. As a 30 matter of fact, the said movable board b is not at such time quite fully pulled back and the weights d are not quite fully elevated, the loaded upright levers f being held just clear, that is, below the cranked projecting arms e^5, e^5 . On completion of filling, the attendant simply pulls said movable board b fully back, that is, a few more inches, which action fully elevates the weights and raises the loaded upright levers f, f , above 40 the cranked projecting arms e^5, e^5 , the movable board b maintaining its fully pulled back position by reason of the weight or settling down of the contained material so that the projecting arms e^5, e^5 lie remote 50 from the catch levers f, f a number of inches. As emptying takes place, the weights d begin to automatically pull-up or pull-in the movable back or board b and said weights are gradually lowered until the 55 tooth f^3 on each loaded upright lever f engages the projecting arm e^5 , and, with continued descent of the weights, the catch levers e, e are removed out of the path of the extremities of the projecting bar b^2 , where- 60 by said catch levers e, e go entirely out of action and the movable back or board b continues to slowly move inwards to pass the material to the lattice a and restrict the dimensions of the hopper.

55 It will be understood that the cranked

projecting arms, catch levers, connecting rods, loaded upright levers, flexible ties, weights and guides, &c. occur at each side of the machine and that no further reference is necessary thereto.

As a modification (shown by Figs. 3 to 6) I may use loaded trip levers g , fulcrumed at g' to the sides c of the hopper A , the same having a jointed element g^2 hinged at g^3 . Each loaded trip lever g is suitably shaped for the extremities of the projecting bar b^2 to work over and for the latter to lock behind. Suitable brackets such as h each with a projecting finger h' are used, and can be attached under the extremities of the projecting bar b^2 . The action in this case is, that, on pulling back the movable board or back b , the projecting fingers h' encounter no obstruction from the hinged elements g^2 and the weighting of the loaded trip levers ensures locking (on the rearward movement of the back b) of the projecting extremities of the bar b^2 , whilst on forward movement, the projecting fingers h' encounter the hinged elements g^2 which cannot move forward beyond the position shown in Fig. 4 and lower or release the trip levers g before the projecting extremities of the bar b^2 encounter same, whereby, the movable board or back b can continue to advance due to the action of the weights. The fact that the fingers h' , advancing inwards, trip the levers g enables me to dispense with the arms e^5 and levers f as will be understood. The letter g^5 denotes a pin to limit the fall of the forward end of the trip lever g . With the object of readily adjusting the weights or load on the movable board or back as the hopper empties and according to the class of material being dealt with I may provide the lower of the removable weight sections, or any weight section, with a projection i and have a movable bracket i' adjustably secured to the hopper side c , said bracket i' being set if required to cut-out a section of the weights on a pre-determined inward movement of the board or back having taken place. The weight boxes if formed with a cavity allow of small loose weights being introduced as may be required.

In order to permit of easy emptying of the hopper, should this be necessary for any reason, I prefer to hinge a section of the movable board or back (say a sixth of the area), and to open this section 1 outwards and downwards securing same when closed by two hinged U shaped clips 2.

The lifting spiked lattice a which occupies a position approximating to the vertical, has for preference two combs j, j' , fulcrumed at the points j, j' , co-operating with it, one arranged at the front and the other at the back.

It is to be understood that the broad

ideas set forth herein may be carried out by different mechanical means and I do not wish to restrict myself as regards mechanical details the arrangements set forth being mentioned to fully set forth the nature of my invention.

Also it is to be understood that my improvements are not restricted to automatic feeding machines wherein the lifting 10 spiked lattice in the hopper is arranged in a position approximating to the vertical or with the fulcrum point of the hinged board fixed more remote with respect to the spiked lattice.

15 I declare that what I claim is:

1. In automatic feeding machines for feeding fibrous material, a lifting lattice, a movable back, pivotal supports therefor, weights acting upon the back, provided 20 guides for the weights, connections between the weights and the back, the movable back being set in one position, and pulled into a further or starting position, catches fulcrumed on the hopper sides, lateral projections on the movable back engaging said 25 catches, and means which act upon the catches fulcrumed on the hopper sides and

put the latter out of action once proper feeding has commenced, as described herein.

2. In automatic feeding machines for feeding fibrous material, a lifting lattice, a movable back, pivotal supports therefor, 30 movable weights, connections between the movable back and the movable weights, weight boxes, lever catches on the weight 35 boxes, and means for cutting out part of the weight as the back moves inwards and the hopper empties for the purposes set forth.

3. In automatic feeding machines, a movable back, weights to act on the back, 40 guides for the weights, connections between the movable back and said weights, and locking devices, said movable back having lateral projections and co-operating with catches pivoted on the sides of the hopper, 45 said back being set in one position and pulled into a further or starting position, and means to automatically disengage the catches pivoted on the sides of the hopper once proper feeding has commenced.

In testimony whereof I have signed my name to this specification:

JOHN WILLIAM WALKER.
